[57] CLAIM

The ornamental design for a clock, as shown and described.

DESCRIPTION

FIG. 1 is a front elevational view of a clock showing my new design, the rear being flat and unornamented;
FIG. 2 is a top plan view thereof, the bottom being a mirror image thereof;
FIG. 3 is a right side elevational view thereof, the left side being a mirror image thereof.

FIG. 2

FIG. 1

FIG. 3
